(57) **CLAIM**

The ornamental design for an insulation resistance tester, as shown and described.

DESCRIPTION

FIG. 1 is a perspective view of an insulation resistance tester showing our new design;

FIG. 2 is a front view thereof;

FIG. 3 is a rear view thereof;

FIG. 4 is a top plan view thereof;

FIG. 5 is a bottom view thereof;

FIG. 6 is a left side view thereof;

FIG. 7 is a right side view thereof;

FIG. 8 is a left side view with the front cover thereof being opened;

FIG. 9 is a front view with the front cover thereof being opened and all the display elements on the panel being on; and,

FIG. 10 is a perspective view showing the tester with its cover opened and probes, shown in phantom line, accommodated in the tester.
